CLAIM

The ornamental design for a combined sensor light with multiple hangers, as shown and described.

DESCRIPTION

FIG. 1 is a front elevational view of a combined sensor light with multiple hangers showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view thereof; and,

FIG. 8 is a second perspective view thereof.

The broken lines in the drawings illustrate portions of the combined sensor light with multiple hangers which form no part of the claimed design. The diagonal lines indicate transparency.
